US0D1110020S

(12) United States Design Patent (10) Patent No.: US D1,110,020 S
(45) Date of Patent: * Jan. 27, 2026

(54) BAG

(71) Applicant: HUIZHOU CHINFAI ELECTRONIC CO., LTD., Huizhou (CN)

(72) Inventor: Zanxiang Li, Huizhou (CN)

(73) Assignee: HUIZHOU CHINFAI ELECTRONIC CO., LTD., Huizhou (CN)

() Term: 15 Years

(21) Appl. No.: 29/980,607

(22) Filed: Dec. 26, 2024

(30) Foreign Application Priority Data

Sep. 13, 2024 (CN) 202430587902.4

(51) LOC (15) Cl. 03-01
(52) U.S. Cl.

USPC D3/301

(58) Field of Classification Search

USPC D3/232-233, 243, 245-247, 249-250, D3/252, 289-291, 301, 303-304;

D7/607, 629, 709; D9/703-705, 707, 709

CPC A45C 3/10; A45C 3/06; A45C 3/04; A45C 3/00; A45C 13/30; A45C 3/001
